[57] CLAIM

The ornamental design for a combined bottle and am-
pule, as shown and described.

DESCRIPTION

FIG. 1 is a front and left side perspective view of a
combined bottle and ampule showing my new design;
FIG. 2 is a top plan view of the bottle shown in FIG. 1;
FIG. 3 is a front elevational view of the bottle shown in
FIG. 1;

FIG. 4 is a rear elevational view of the bottle shown in
FIG. 1;

FIG. 5 is a left side elevational view of the bottle shown
in FIG. 1;

FIG. 6 is a right side elevational view of the bottle
shown in FIG. 1;

FIG. 7 is bottom plan view of the bottle shown in FIG.
1;

FIG. 8 is a front and left side perspective view of a
combined bottle and ampule shown without the ampule
for clarity of illustration;

FIG. 9 is a top plan view of the bottle shown in FIG. 8;
FIG. 10 is a front elevational view of the bottle shown
in FIG. 8; and

FIG. 11 is a left side elevational view of the bottle
shown in FIG. 8.
